US0D1001592S

(12) **United States Design Patent** (10) **Patent No.:** **US D1,001,592 S**
(45) **Date of Patent:** **** Oct. 17, 2023**

(54) **CONTAINER**

(71) Applicant: **Hydrojug, Inc.**, Ogden, UT (US)

(72) Inventors: **Hayden Wadsworth**, Ogden, UT (US);
Jeffrey Steel, Midland Park, NJ (US);
Matthew Earl Meyer, Bountiful, UT (US)

(73) Assignee: **HYDROJUG, INC.**, Ogden, UT (US)

(**) Term: **15 Years**

(21) Appl. No.: **29/804,409**

(22) Filed: **Aug. 19, 2021**

(51) **LOC (14) Cl.** **07-01**
